VACUUM CLEANER CASING

Robert J. McKnight, Springfield, Ohio, assignor to Orly Musgrave, Springfield, Ohio

Filed Sept. 24, 1959, Ser. No. 57,661

Term of patent 14 years

(Cl. D9—2)

I claim:

The ornamental design for a vacuum cleaner casing, substantially as shown.
